United States Patent

Des. 235,837
Patented July 15, 1975

235,837

CONTAINER SUPPORT

Thomas E. Little, 2610 Nicholson,
Houston, Tex. 77008

Filed Jan. 23, 1974, Ser. No. 435,783

Term of patent 14 years

Int. Cl. D7—07

U.S. CL. D7—189

Fig. 1

Fig. 2

Fig. 3

Fig. 4

FIG. 1 is a perspective view of the container support taken from the top and one side and showing my new design;

FIG. 2 is a similar perspective view but taken from the back;

FIG. 3 is a top plan view; and

FIG. 4 is a bottom plan view.

I claim:

The ornamental design for a container support, substantially as shown.
